UNITED STATES PATENT OFFICE.

LEONARD M. LARSEN, OF BIRNAMWOOD, WISCONSIN.

MUSIC-LEAF TURNER.

1,277,608.

Specification of Letters Patent. Patented Sept. 3, 1918.

Application filed October 31, 1916. Serial No. 128,747.

To all whom it may concern:

Be it known that I, LEONARD M. LARSEN, a citizen of the United States, residing at Birnamwood, in the county of Shawano and State of Wisconsin, have invented certain new and useful Improvements in Music-Leaf Turners, of which the following is a specification.

This invention has relation to music leaf turner attachments for pianos and the nature and objects thereof will be readily apparent to those skilled in the art to which it appertains, in the light of the following explanation of the accompanying drawings, illustrating what I now believe to be the preferred embodiment, or mechanical expression, of my invention from among other forms and arrangements within the spirit thereof or the scope of the appended claims.

20 However, an object of the invention is to provide a music leaf turning device in the nature of an attachment which may be readily applied to a standard piano, with a view to concealing as much of the apparatus as possible, and to provide an apparatus which may be readily actuated by a foot pedal arrangement to turn the leaves of the music successively without distracting the attention of the player.

25 Another object of the invention is to provide in a music leaf turner of the character described, a new and novel means for successively releasing one sheet of the music after another upon successive actuations of the foot pedal.

In addition to the foregoing my invention comprehends improvements in the details of construction and arrangement of the parts, without departing from the spirit of the invention or the scope of the appended claims.

In the accompanying drawings in which similar and corresponding parts are designated by the same characters of reference throughout the several views in which they appear;

Figure 1 is a view in end elevation of a piano illustrating the application thereto of my invention.

Fig. 2, is a detail sectional view illustrating a portion of the clamping mechanism for securing the attachment to a piano.

Fig. 3, is a view in front elevation of the device shown in the preceding figure.

Fig. 4, is a detail view on an enlarged scale of the fork for releasing the leaf engaging bars, and correlated parts.

Fig. 5, is a view of the end portion of the clamp for securing the attachment to a piano.

Fig. 6, is a detail sectional view of the bar 60 for supporting the music leaf engaging bars, and illustrating the manner in which the bars are associated therewith.

Fig. 6^a, is a detail view of an extension 65 for said supported bar.

Fig. 6^b, is a detail sectional view illustrating the manner of operation of the leaf engaging bar releasing means.

Fig. 7, is a horizontal detail sectional view 70 illustrating the manner in which a leaf engaging bar is pivotally connected to the supporting bar thereof.

Fig. 8, is a detail view in front elevation of one of the clips for engaging a sheet of music. 75

Fig. 9, is a transverse section taken through the clip of the preceding figure.

Fig. 10, is a vertical sectional view in detail illustrating the foot pedal for actuating the apparatus. 80

Fig. 11, is a sectional detail view illustrating the fulcrum block for supporting the pedal actuated lever.

Fig. 12, is a transverse sectional view taken through the block of the preceding 85 figure.

Fig. 13, is a detail sectional view of the intermediate portion of the pedal actuated lever, and

Fig. 14, is a detail view in plan of the 90 said lever.

With reference to the drawings, and particularly Fig. 1, which is a view of a piano illustrated in end elevation, the top board 1, of the piano in accordance with standard 95 construction is formed with an outwardly extending overhanging ledge 2, and in addition thereto a depending portion 3 is formed. The present invention contemplates the support of the attachment upon the top board 1, 100 and to that end an angular clamping element 4 is applied to the top board at the rear longitudinal edge thereof, the downwardly extending portion of the clamp 4 having a set screw 5 which is adapted to 105 bear against the edge of the board. At the forward edge of the top board there is provided a second angular member 6, having a downwardly extending portion 7, which rests against the ledge and depending portion 3, the top members of the clamps 4 and 6, being then connected by means of connect-

ing strip 8 permanently secured at its forward end to the clamp 6 and adjustably secured to the clamp 4 by means of a set screw 9. The depending portion 7 of the clamp 6 is provided with a vertically elongated opening 10, in which the reduced end 11 of a block 12 is designed for vertical movement. A set screw 13 is seated in a correspondingly threaded opening in the forward end of the reduced portion 11, said set screw being provided with a head 14 and a flange 15. The flange 15 is adapted to engage the outer face of the portion 7, and obviously by tightening up the set screw subsequently to adjusting the block within the slot said slot may be retained in adjusted relation to the clamp. The inner surfaces of the clamping member 2 as well as the clamping member 4 may be covered with a thickness of felt or the like 16 to prevent injury to the piano. The opposite surface of the block 12 is similarly provided. These clamping members are illustrated in detail in Figs. 2, 3 and 5.

The block 12 is provided with a number of internally threaded openings 17 disposed in longitudinally spaced relation, either of which is adapted to receive the correspondingly threaded ends 18 of a leaf engaging supporting bar 19. By providing a number of openings, the bar 19 may be disposed toward or away from the face of the piano to compensate for different pianos in which the ledge 2 is disposed farther or nearer to the front part of the piano. The said bar 35 is adapted to depend vertically beneath the block 12 and is formed of a solid section and a telescoping outer section 20, the said sections being movable relatively to each other and secured against movement subsequent to adjustment by means of a set screw 21. The lower end of the section 20 is bent outward at a slight angle with relation to the vertical, said bent portion being inclined to coincide with the degree of inclination of the music supporting plate 22 of the piano. The bent extremity 23 of the rod 19 is formed with a plurality of annular grooves 24 in each of which the looped end 25 of a leaf engaging rod 26 is seated. The 40 leaf engaging rods 26 of which three have been illustrated, are thus capable of rotation upon the bent extension 23, in a plane at right angles thereto. A coil spring 27 is provided for each rod, said spring being 45 adapted to encircle the extension 23 with one end thereof secured thereto, and the opposite end wrapped about its corresponding rod 26. In this manner each rod is urged toward the left of the player facing the piano, and is retained against such movement by a device to be presently described. A rod 19^a having an offset may be provided as shown in Fig. 6^a to permit the disposal of the inner end of the rod 26 near the piano.

65 At the outer terminal of each of the rods

26, there is provided a clamp comprising a pair of stationarily mounted depending fingers 28 having one of their ends wrapped about the rod, said members being disposed in suitable spaced relation. For each of the 70 members 28 there is a corresponding coacting member 29 provided, having spaced ears 30 which are apertured to receive the rods 26', the opposite ends of said members 29 being connected by a strip 31 having at its 75 intermediate portion, an upstanding member 32. A coil spring is encircled about the rod 26' between each pair of clamping members 28 and 29, one terminal of each spring being inserted in the opening of each rod, 80 while the other terminal is adapted to bear upon the other face of the member 29, to urge said member into engagement with the member 28. A finger piece 33 is secured to the rod between the clamps and adjacent the 85 finger piece 32 whereby upon bringing said finger pieces together the members 29 of each clamp are simultaneously disengaged from their coacting members, so as to receive therebetween a sheet of music. Upon 90 releasing the finger pieces, the clamps are automatically brought into engagement upon the sheets of music. The rod 26' is preferably secured to the member 33. A member of rubber or the like 34 may be provided upon the front face of each of the members 29 to prevent injury to the piano when said clamps are rapidly swung around under the influence of the spring 27.

Upon the horizontal member of the clamp 100 6 a standard 35 is erected and has its upper terminals bifurcated to guide for vertical movement a horizontal rod 36 to the front terminal of which a downwardly extending rod 37 is connected. Said rod 37 is adapted 105 to extend through a vertical opening in the end of the rod 36, and a set screw in the latter serves to secure the rod 37 in a vertically adjusted position. The rear end of the rod 36 is inserted in the head portion 38 of 110 a vertical rod 39 located at the rear of the piano. The head 38 is designed to provide a rigid connection between the rods 39 and 36, whereby upon vertical reciprocation of said rod 39, the rod 36 may be moved vertically. A set screw 40 extending through the head 38 is adapted to engage the rod 36 to permit relative adjustment of the parts. The rod 39 is formed in telescoping sections secured together by means of set screws 41. 115 The rod 39 is adapted for vertical reciprocation in the end of eyebolts 42 secured in the rear board of the piano. The lower end of the rod 39 is adjustably connected to a lever 43 disposed adjacent the floor, and which is fulcrumed in a fulcrum block 44 supported upon a platform 45 which is supported upon rubber supports 46, one of which is provided at each corner of the platform. The fulcrum block 44 which is shown 120

130

in detail in Figs. 11 and 12, is formed with a groove 47 in which the lever 43 is designed to rest, the bottom of the groove being convexed as at 48 and provided centrally with 5 an upstanding pin portion 49. The lever 43 is provided with upwardly flared openings 50 through which the pin passes, while the under side of the lever is designed to rest upon the convexed portion 48. Obviously 10 the lever is permitted a rocking movement in a vertical direction with a sidewise movement. The forward end of the lever 43 is brought adjacent the usual foot pedals of the piano, and its extremity which is normally 15 disposed in vertical spaced relation above the floor is hingedly connected to a foot pedal 51 which is normally inclined downwardly in the opposite direction and is hingedly connected at 52 to a platform 20 53. A leaf spring 54 beneath the foot pedal tends to retain the pedal in raised position, and consequently the lever 43. Vertical guides 55 are disposed at each side of the lever 43 and foot pedal 51 adjacent their 25 point of connection and a bar 56 connects the guides whereby vertical movement of the pedal and lever is limited by engagement of the hinged member with said bar. The platform is supported upon rubber sup- 30 ports in a manner similar to the platform 45. Obviously by depressing the foot pedal 51 the lever 53 is likewise depressed at its forward end, raising its rear end and thereby imparting a vertical movement to the 35 rod 39 and the rod 36.

To the lower end of the rod 37 which is illustrated in detail in Fig. 4, there is provided a horizontal bar 57, vertically adjustable upon said rod 37 and provided at 40 one end with a downwardly extended portion 58, having a socket therein for the reduced extremity 59 of the shank 60 of a member having a plurality of depending tines, of various lengths, the longest of 45 which is designated 61 and the remainder respectively as 62 and 63. The reduced extremity of the shank 60 is retained within the pocket by means of a set screw 64 which passes through a threaded opening in the 50 terminal 58 of the rod 57. In this manner rotative adjustment of the prongs of the forked device is provided relative to the supporting bar thereof 67.

In the operation of this device, the music 55 is rested upon the support 22 therefor of the piano, and the leaves to be turned are separately clasped by one of the clamps at the terminal of each of the rods 26. The rods 26 are then moved to the right and one 60 of said rods disposed between each of the tines 61, 62, and 63 of the forked device. This arrangement is substantially as shown in Fig. 6 and 6^b, from which it will be noted that in cross section the rods 26 are dis- 65 posed in vertical spaced relation, as well as

in horizontally spaced relation. The tines of the forked device being thus engaged upon the rods 26, swinging movement toward the left of said rod is precluded. When the first sheet is to be turned, the foot pedal 51 is depressed, thereby raising the rod 39 vertically and also the rods 36 which in turn through the medium of the devices previously described impart a vertical movement to the forked member through a predetermined distance. The first upward movement of the forked device results in the release of the lowermost one of the rods 26, permitting the same to move toward the left under the influence of its spring, thereby turning over 80 the leaf. During the release of said rods 26, the next succeeding rods are released from the tines against which they are held, and permitted to engage the next succeeding tine. Upon the second depression of the foot 85 pedal, the forked device is again raised to a greater distance, permitting the release of the rod 26 which through the first movement has been brought into engagement with the lowermost tine 61. The next rod 26 is released in a similar manner. Any number of rods 26 may be provided of course but for all practical purposes three have been found to be amply sufficient.

While I have illustrated and described my 95 invention with some degree of particularity, I realize that in practice various alterations thereover may be made, and I therefore reserve the right and privilege of changing the form of the details of construction and arrangement of the correlated parts, without departing from the spirit of the invention or the scope of the appended claims.

Having thus described my invention what I claim as new and desire to secure by Letters Patent is:

1. A music leaf turning attachment for pianos, including a clamping element adapted to engage the top board of a piano, a depending rod secured to the forward end of the clamp and having an outwardly bent terminal provided with a plurality of annular grooves, a corresponding number of leaf engaging rods having looped terminals seated within the grooves, coil springs engaging 110 said bent terminal and rods to urge them toward the left, clasps at the terminals of each rod adapted to engage a sheet of music, a depending fork having a plurality of tines of varying lengths, between which a rod is 115 adapted to enter and be held toward the right, a foot pedal arrangement for producing vertical movement of said fork to successively release the rods and permit their movement toward the left. 120

2. A music leaf turning attachment for pianos, including a clamping device adapted to engage the top of a piano, a depending rod secured to the forward end of the clamp and having a plurality of leaf engag- 125

ing rods pivotally connected to the terminal of the rod and adapted for oscillation, resilient means for urging said rods toward the left, a forked device having a plurality of tines of various lengths between which the rods are adapted to enter to retain said rods toward the right, a normally horizontal rod extending transversely above the piano, a rod depending from its forward end having adjustable connection with the fork, a vertical rod disposed at the rear of the piano and having rigid connection with the horizontal rod, and a foot pedal arrange-
10

ment beneath the piano for imparting a vertical movement of the vertical rod, and horizontal rod thereby raising the fork to a pre-determined distance, for successively releasing the rods to permit their movement toward the left.

In testimony whereof I affix my signature 20
in presence of two witnesses.

LEONARD M. LARSEN.
